BRASSIÈRE

William Kurland, Great Neck, N. Y.

Application August 15, 1950, Serial No. 179,430

6 Claims. (Cl. 2—42)

1

This invention relates to women's brassières and more particularly, it relates to brassières which are so constructed that the provide a more graceful and positive uplift for the feminine form without binding and without curling or buckling of reinforcing strips.

There have been numerous brassières which have been developed in an attempt to provide an uplift effect for the breasts without discomfort to the wearer. These brassières depend on bones or artificial stays, elastic bands gripping the torso in a horizontal fashion, or some such, to give the necessary uplift effect. In general, they might be characterized as being exceedingly uncomfortable to the wearer, particularly in the shoulder straps, although tolerated as a necessary concomitant to the fashion demands of the day. In general, they provide a partial uplift which is not at all satisfactory.

This invention has as its object to provide a means for supporting the breasts with both a vertical and a transverse pull of the shoulder straps and thus provide an increased and more positive lifting effect. It is an object of this invention to provide a brassière in which buckling and rolling of the reinforcing bands or strips is prevented. And as yet another object, this invention desires to provide a brassière in which the tendency of the shoulder straps to slide off the shoulders of the wearer is lessened. Other objects will be apparent in the latter portions of this specification.

This invention attains these objects by providing a brassière in which there is longitudinally flexible reinforcing bands attached to the lower portion of each of the breast supporting cups. The band from each cup is attached in the center of the garment to each other at a predetermined angle so that the bottom portion of the brassière resembles an inverted V when worn. Thus the strain on each shoulder strap is not only vertical, as is the usual case, but is also in a slanted direction from the opposite side. Each breast is partially supported by each shoulder strap. The band is sewed along the bottom of the cup and meets the band from the other cup in the center of the garment. In order to maintain the angle at their juncture in a relatively fixed position, a rigid non-flexible piece of fabric is inserted at the juncture and the bands are sewed to this piece. The transverse force pulling each band upwardly and across the body results in a very firm uplift. It has been found that if the bands meet each other at an angle of substantially 112°, a very comfortable uplift is provided.

2

A further feature of this invention comprises the manner of construction of the elastic reinforcing bands. This elastic band has an inner strip or core of elastic which is covered by a sheath of stretchable elastic covering so that it covers the core both in front and one in back. The material of inner elastic strip has greater stretchability than the external elastic covering sheath. By controlling the differential of relative stretch between the internal and external layers the over-all stretchability of the bands can be controlled. The internal elastic material may be easily changed or replaced in manufacture so as to give the exact amount of tension necessary to alleviate binding and undue strain against the body, and different models may be offered to the public with no increase in manufacturing patterns or forms. The change in the garment is one which is internal and unobservable on the surface.

To further maintain a sub-control of the stretch, V-shaped stitching is applied to the reinforcing bands. It can be seen that there is a considerable strain placed on the reinforcing bands because they have a transverse force placed on them pulling them upwardly and across the body of the wearer. This increased strain increases the tendency of the reinforcing bands to buckle. To prevent this, this invention proposes to apply stitching as a flexible shirring in a series of continuous V's to the reinforcing bands. The V runs from the top to the bottom across the reinforcing bands with the angle of the V controlled so that it is substantially identical to the V formed both by the reinforcing bands and the tops of the cups. By thus using the same angles throughout, the forces are co-ordinated and a non-buckling smooth reinforcing band is produced. The amount of stretch possible in any localized region, namely between the two legs of the V, is limited and localized, so that it cannot extend beyond the row of stitches. Thus while the stretch is generally linear in the direction of the shoulder strap, the over-all stretch is broken down into segments each of which is controlled as to maximum extension. The band follows the natural lines of a woman's body without creating an excess of tension so that the garment fits and conforms in a natural manner.

A still further feature of this invention is found in the construction of the breast supporting and containing cups. These cups are subject to a certain amount of distortion due to the twisting forces to which they are subjected. A slight amount of wrinkling is caused and an un-

desirable uneven contour results. To restore the smoothness which is desired, the cups are cut along their upper edge so that a substantially straight line is formed from the reinforcing band of one side up along the upper edge of the opposite cup. This is done on both sides so that the upper edges of the cups form a V at their juncture which is substantially the same as that formed by the reinforcing band. The V begins at one shoulder strap, goes across and down to the center of the brassière, and then upwardly along the upper edge of the other cup. This is a minor refinement which has proved to be a simple method of eliminating the aforementioned wrinkles.

Several additional pleasing features result from a brassière constructed as described in this specification. Because of the upward direction across the body which the reinforcing bands assume, their uppermost ends pass around the curved portions of the body and thus part of their length is held away from contact with the skin. This results in increased comfort for the wearer.

Another useful effect of the transverse pull of the reinforcing bands is the effect which it has on the shoulder straps. They are pulled slightly toward the center of the garment and this strain serves to decrease their tendency to slip off the shoulders of the wearer. If the strain from one side of the body should suddenly decrease due to a rapid movement of the body, there is still some pull from the other side, so that no opportunity is provided to slip off during a slack moment.

The following example shown in the figures of the accompanying drawings is given for illustrative purposes only and it is not deemed limiting as the scope of the invention is to be determined by the appended claims including such variations within the limits of the invention as would suggest themselves to one skilled in this art.

Figure 1 is a front view of the brassière in the shape it assumes when being worn. Figure 2 is a back view of the brassière, showing the reverse construction of the garment. Figure 3 is a front view of the brassière with the component parts shown in detail. Figure 4 is a section through 4-4, showing the construction of the reinforcing band in cross-section. Figure 5 is a cut away view of the reinforcing band showing the component parts and the stitching in detail. Figure 6 is a cross-section through 6-6 and shows the construction of the joint between the two reinforcing bands.

More particularly in the drawings, the brassière is composed of upper cup sections 11 and 15, lower cup sections 12 and 16, supporting straps 22 and 23, and back sections 20 and 32. The cup sections are each formed in two pieces and stitched along lines 17 and 18 in order to present a more curvaceous appearance in the garment. In order to provide a flat, body-clinging element, the two reinforcing bands 13 and 14 are provided. The reinforcing bands are formed from a strip of rubber 38, covered with a material 13 which is flexible along its longitudinal length only. The upper portion is covered with a thin strip of non-flexible material 29 in order to give it rigidity, and to this the lace or net or fabric 12 which comprises the cup of the brassière is stitched. Stitching 39 and 40 holds this firmly in place, as shown in Figure 5.

The reinforcing strips 13 and 14 come toward the center of the brassière in the shape of an inverted V and are joined at center portion 35. 75

The details of construction at this juncture are shown in Figure 6. The longitudinally elastic fabric 13, 14, 36 and 37 are stitched to a member 35 of non-resilient material to form a firm junction and to hold the reinforcing strips 13 and 14 fixedly at a predetermined angle. It has been found that a comfortable angle and one which will accomplish the objects of this invention is 112°. If the reinforcing strips are joined at this or some other predetermined angle, then the upper cup sections 11 and 15 are constructed so that their upper edges 26 and 27 meet at their juncture at the center of the brassière to form an angle which is substantially the same as the angle between the reinforcing strips. Thus a substantially straight line strain is provided from the shoulder strap to the opposite bottom portion of the brassière.

The reinforcing bands are stitched with serpated stitching 19 in order to permit the bands to be stretched along their lateral or longitudinal length. This stitching is placed in a series of continuous inverted V's as shown at 33 and 34. The angle between the V's is controlled to be substantially the same as that between the reinforcing strips and between the upper cup sections.

What I claim is:

1. A brassière comprising a pair of breast-supporting cups having substantially non-stretchable margins, each cup being formed with an upper substantially apex-shaped portion and also shaped with a lateral inwardly directed substantially pointed portion, both pointed portions being interconnected whereby both cups form with one another an upper upright V-shaped cutout and a corresponding lower inverted V-shaped cutout, a back section of substantially non-stretchable material for and stitched to the outer side of each cup and extending downwardly below the bottom margin of the associated cup to constitute a shoulder therewith, a reinforcement band of stretchable material extending inwardly from each shoulder and joined along its length to the lower margin of the associated cup as well as joined to the associated shoulder and having its bottom edge substantially aligned with the bottom edge of the associated back section, means interconnecting inner ends of said reinforcement bands at the vertex of the lower inverted V-shaped cutout, and a shoulder strap extending from the apex of each cup to the corresponding back section.

2. A brassière according to claim 1, in which said interconnecting means constitute a member of non-stretchable material.

3. A brassière according to claim 1, in which said reinforcing bands comprise an outer stretchable sheath and an inner elastic strip having a stretchability greater than that of the sheath, the degree of stretchability of the strip being optional so that the net stretchability of the garment is variable without change of its external shape.

4. A brassière according to claim 1, in which said reinforcing bands comprise an outer stretchable sheath and an inner elastic strip having a stretchability greater than that of the sheath, the degree of stretchability of the strip being optional so that the net stretchability of the garment is variable without change of its external shape, with the addition that the stretchable sheath is joined to the elastic strip by a series of V-shaped flexible stitching defining subsegments of stretch within the bands.

5. A brassière according to claim 1, with the addition of flexible stitching along the reinforcing bands in a series of V-shapes, the angle of these V-shapes being substantially the same as the angle of the V-shape formed by and between the reinforcing bands.

6. In a brassière comprising the combination which comprises a pair of breast-supporting cup sections having substantially non-stretchable margins, each cup section being formed with an upper substantially apex-shaped portion and also shaped with a lateral inwardly directed substantially pointed portion, both pointed portions being interconnected whereby both cups form with one another an upper upright V-shaped cutout and a corresponding lower inverted V-shaped cutout, a back section of substantially non-stretchable material extending from the outer side of each cup and also extending downwardly below the bottom margin of the associated cup to form a shoulder therewith whereby said shoul-

ders form with the lower edges of the cup sections a V-shaped recess, and a V-shaped insert of substantially stretchable material for said recess and joined edgewise to the edges of the recess and having a vertex portion of non-stretchable material.
